LEAF TRANSFERRING DEVICE IN CIGAR MACHINES

Karl Erik Granstedt, Stockholm, Sweden, assignor to Aktiebolaget Formator, Stockholm, Sweden, a Swedish joint-stock company

Application April 24, 1931, Serial No. 532,659
In Sweden May 3, 1930

18 Claims. (Cl. 131—39)

The present invention relates to a leaf transferring device in cigar machines of the type in which a leaf carrier receives a cut tobacco leaf from a cutting pad and is moved to a wrapping device, in which the tobacco leaf is removed from the carrier and wrapped about a bunch. For this purpose the leaf carrier is made to perform an oscillating movement about its shaft and this shaft is made to move parallel to itself. In the 5 machines hitherto used these movements are effected by means of levers controlled by slot drums, slot plates or the like, said levers actuating the leaf carrier through the intermediary of hinged arms or the like. This arrangement involves complicated movement-transferring devices having a great number of swivel points with consequent large friction.

These disadvantages are eliminated by the 10 present invention, which is principally characterized in that the shaft of the leaf carrier or an extension thereof is adapted to be controlled by a curve slot or a curve track in such a manner that the shaft moves parallel with the profile of the curve slot respectively the curve track. 15 The most simple way of doing this is by arranging the swivel shaft of the leaf carrier or an extension thereof to run in a curve slot or against a curve track in order to impart to the leaf carrier such a movement that the shaft thereof moves 20 parallel with itself. To provide for the oscillating movements of the leaf carrier the carrier is provided with an arm which is arranged to run in a second curve slot or against a curve track provided for this purpose. Said curve slots may 25 be arranged in the same plate but it is preferable to arrange each curve slot in a separate plate in order to provide for setting of the curve slots individually and independent of each other. The new arrangement has the advantage that the 30 number of parts required for the construction is reduced. Above all the number of swivel points will be less, whereby friction will be reduced and the construction will be more lasting and require less re-setting.

40 A preferred embodiment of the invention is shown in the accompanying drawing. Fig. 1 is a side view, partly in section, and Fig. 2 a horizontal view. Fig. 3 is an enlarged detail in section showing the arrangement permitting relative adjustment of the two plates.

The leaf carrier 1 is of the type usually employed in cigar machines and is provided with a suction chamber disposed at and connected to a hollow shaft 2. The shaft 2 is pivotally supported by a hollow arm 4 which in turn by means

of a hinge 8 is connected to a hollow arm 3. This arm 3 is attached to a hollow, pivotally mounted shaft 9, the interior of which is in connection with a suction device not shown. According to the invention the shaft 2 is provided with a guide 60 tap 2a, which either directly or through the intermediary of a roller 5 is arranged to slide in a curve slot 22 provided in a flat plate 6. The curve slot is so formed and the extension thereof is such that the leaf carrier through the intermediary of the shaft 9 and the arms 3 and 4 is moved from the cutting pad 25 to a wrapping device (not shown), having first passed over an adhesive applying device not shown. To the free 65 end of the guide tap 2a projecting above the plate 6 is fixed an arm 7 which by means of a pin, or a roller 17 provided on the pin, is arranged to slide in a curve slot 23 in a second plate 18. This curve slot is positioned in relation to the curve slot 22 in such a manner that the leaf carrier while moving along the slot 22 is also given a rotating movement in order that the leaf carrier may take up the correct positions 70 relatively to the cutting pad, the adhesive applying device and the wrapping device.

75 The flat plates 6 and 18 provided with curve slots are arranged above and at a certain distance from each other and are supported by a bracket 20 fixed to the bearing 30 of the shaft 9 and by a standard 34 fixed to the frame of the 80 machine. The lower plate 6 rests directly on the said supports (the bracket 20 and the standard 34), the upper plate 18 through the intermediary of distance rings 31. The plates are fixed to the support by means of screw bolts 26, 32 respectively 85 27, 33 and the holes provided in the plates and the distance pieces for the bolts, as well as the holes in the plate 6 for the distance pieces, are so large as to enable the plates to be individually 90 set or adjusted horizontally, i. e. in their own 95 planes.

The shaft 9 is given an oscillating swivelling movement by means of the following arrangement. On the lower end of the shaft 9 is fixed a conical toothed segment 11 in engagement with a second toothed segment 12 fixed to a shaft 13. The toothed segment 12 is provided with an arm 14 carrying a roller 15. This roller 15 is arranged to slide in a curve plate 16, attached to a rotating shaft 19 of the cigar machine.

100 As mentioned above the guide tap 2a respectively the roller thereof and the arm 7 respectively the roller thereof may also be arranged to run against curve tracks instead of running in curve slots, or the guide tap 2a respectively the arm 7 110

may be provided with a yoke-shaped member, the jaws of which enclose a curved bar or rail.

What I claim is:—

1. In a cigar machine the combination of a leaf carrier, a rock shaft, by means of which said leaf carrier is rotatably supported, means for giving the leaf carrier an oscillating movement about said rock shaft, a driving shaft, a curved track and operating means for causing the rock shaft to move parallel with itself along said curved track, said operating means forming a suction conduit from said driving shaft to said leaf carrier. 80
2. In a cigar machine the combination of a leaf carrier, a rock shaft, by means of which said leaf carrier is rotatably supported, means for giving the leaf carrier an oscillating movement about said rock shaft, said means consisting of an arm on the rock shaft, and of a curved track, against which the arm is adapted to travel, a driving shaft, a second curved track and operating means for causing the rock shaft to move parallel with itself along said second curved track, said operating means forming a suction conduit from said driving shaft to the leaf carrier. 85
3. In a cigar machine the combination of a leaf carrier, a shaft, by means of which said leaf carrier is rotatably supported, means for giving the leaf carrier an oscillating movement about said shaft, said means consisting of an arm on the shaft, and of a curved track, against which the arm is adapted to travel, a second curved track and means for causing the shaft to move parallel with itself along said second curved track, said curved tracks being arranged on two plates. 90
4. In a cigar machine the combination of a leaf carrier, a shaft, by means of which said leaf carrier is rotatably supported, means for giving the leaf carrier an oscillating movement about said shaft, said means consisting of an arm on the shaft, and of a curved track, against which the arm is adapted to travel, a second curved track and means for causing the shaft to move parallel with itself along said second curved track, said curved tracks being arranged on two plates, said plates being arranged in two planes which are parallel with each other. 95
5. In a cigar machine the combination of a leaf carrier, a shaft, by means of which said leaf carrier is rotatably supported, means for giving the leaf carrier an oscillating movement about said shaft, said means including a curved track, a second curved track and means for causing the shaft to move parallel with itself along said second curved track, said two tracks being arranged on two parts, which are arranged the one directly above the other. 100
6. In a cigar machine the combination of a leaf carrier, a shaft, by means of which said leaf carrier is rotatably supported, means for giving the leaf carrier an oscillating movement about said shaft, said means consisting of an arm on the shaft, and of a curved track, against which the arm is adapted to travel, a second curved track and means for causing the shaft to move parallel with itself along said second curved track, said curved tracks being arranged on two plates, said plates being arranged the one above the other. 105
7. In a cigar machine the combination of a leaf carrier, a shaft, by means of which said leaf carrier is rotatably supported, means for giving the leaf carrier an oscillating movement about said shaft, said means consisting of an arm on the shaft, and of a curved track, against which the arm is adapted to travel, a second curved track and means for causing the shaft to move parallel with itself along said second curved track, said plates being arranged the one above the other. 110

allel with itself along said second curved track, said curved tracks being arranged on two plates, said plates being arranged the one above the other in two planes which are parallel with each other.

8. In a cigar machine the combination of a leaf carrier, a shaft, by means of which said leaf carrier is rotatably supported, means for causing the leaf carrier to oscillate about said shaft, said means including a curved track, a second curved track and means for causing the shaft to move parallel with itself along said second curved track, said curved tracks being arranged on two plates and means for adjusting said plates individually in their own planes. 115

9. In a cigar machine the combination of a leaf carrier, a shaft, by means of which said leaf carrier is rotatably supported, means for causing the leaf carrier to oscillate about said shaft, a curved track, included in the said means, a second curved track, and means for causing the shaft to move parallel with itself along said second curved track, said curved tracks being arranged on two plates, said plates being arranged the one above the other in two planes which are parallel with each other and means for adjusting said plates individually in said planes. 120

10. In a cigar machine the combination of a leaf carrier, a shaft, by means of which said leaf carrier is rotatably supported, means for giving the leaf carrier an oscillating movement about said shaft, a curved track and means for causing the shaft to move parallel with itself along said curved track, a driving shaft, and a single toggle lever forming a channel between the leaf carrier shaft and the driving shaft. 125

11. In a cigar machine the combination of a leaf carrier, a shaft, by means of which said leaf carrier is rotatably supported, means for giving the leaf carrier an oscillating movement about said shaft, a curved track and means for causing the shaft to move parallel with itself along said curved track, a driving shaft, a single toggle lever connecting the leaf carrier shaft and the driving shaft, the driving shaft, the toggle lever and the leaf carrier shaft being hollow and communicating with each other. 130

12. In a cigar machine the combination of a leaf carrier, a shaft, by means of which said leaf carrier is rotatably supported, a curved track, means for causing the leaf carrier to oscillate about said shaft, said means including said curved track, a second curved track, means for causing the shaft to move parallel with itself along said second track, said curved tracks being arranged on two plates, said plates being arranged the one above the other, and distance members adapted to space apart said plates vertically. 135

13. In a cigar machine the combination of a leaf carrier, a frame, a shaft, by means of which said leaf carrier is rotatably supported, a curved track, means for causing the leaf carrier to oscillate about said shaft, said means including said curved track, a second curved track, means for causing the shaft to move parallel with itself along said second track, said curved tracks being arranged on two plates, said plates being arranged the one above the other, fastening members for securing the plates in the frame, said fastening members being adapted to pass through holes in one of the plates. 140

14. In a cigar machine the combination of a leaf carrier, a frame, a shaft, by means of which said leaf carrier is rotatably supported, a curved track, means for causing the leaf carrier to os- 145

cillate about said shaft, said means including
5 said curved track, a second curved track, means
for causing the shaft to move parallel with itself
along said second curved track, said curved
tracks being arranged on two plates, said plates
being arranged the one above the other, fasten-
10 ing members for securing the plates in the frame,
distance members adapted to space apart said
plates vertically and being provided with holes
to receive said fastening members.

15. In a cigar machine the combination of a
leaf carrier, a shaft, by means of which said leaf
carrier is rotatably supported, means for caus-
ing the leaf carrier to oscillate about said shaft,
15 said means consisting of an arm on the shaft
and of a curved track, against which the arm is
adapted to travel, a second curved track, means
for causing the shaft to move parallel with itself,
said curved tracks being arranged on two plates,
20 which are arranged the one above the other, and
are spaced apart vertically, said arm being lo-
cated in the space between said plates.

16. In a cigar machine the combination of a
leaf carrier, a frame, a shaft, by means of which
25 said leaf carrier is rotatably supported, a curved
track means for causing the leaf carrier to oscil-
late about said shaft, a second curved track,
means for causing the shaft to move parallel
with itself along said second curved track, said
30 curved tracks being arranged on two plates, said
plates being arranged the one above the other,
the lower one of said plates being mounted di-

rectly on the frame, distance members on the
upper side of the lower plates, the upper plate
resting on said distance members.

17. In a cigar machine, the combination of a
leaf carrier, a shaft, by means of which said
leaf carrier is rotatably supported, a curved
track, means for causing the leaf carrier to
oscillate about said shaft, said means including
said curved track, a second curved track, means
for causing the shaft to move parallel with itself
along said second track, said curved tracks being
arranged on two plates, said plates being ar-
ranged in two planes which are parallel with each
other, and distance members adapted to space
20 apart said plates, one of the plates being pro-
vided with holes for said distance members.

18. In a cigar machine the combination of a
leaf carrier, a shaft, by means of which said leaf
carrier is rotatably supported, means for giving
the leaf carrier an oscillating movement about
said shaft, said means consisting of an arm on
the shaft, and of a curved track, against which
the arm is adapted to travel, a second curved
track and means for causing the shaft to move
parallel with itself along said second curved
track, a driving shaft, a single toggle lever con-
necting the leaf carrier shaft and the driving
shaft, the driving shaft, the toggle lever and the
leaf carrier shaft being hollow and communi-
cating with each other.
